(E. L. Seymour)

UNITED STATES PATENT OFFICE.

EDW. L. SEYMOUR, OF NEW YORK, N. Y., ASSIGNOR TO DANL. B. BROWN.

GOLD-SEPARATOR.

Specification of Letters Patent No. 11,712, dated September 19, 1854.

To all whom it may concern:

Be it known that I, EDWARD L. SEYMOUR, of the city, county, and State of New York, chemist, have invented a new and improved apparatus for separating or extracting metallic or native gold from auriferous sands and gravels and all such rocks, deposits, and materials which contain particles of metallic or native gold.

10 My invention and improvement consist in a novel useful and profitable application of mechanical contrivances, by means of which, after my new plan and method cheap and simple apparatus of various size and form 15 can be easily constructed, in which, through the agency of either water or air, or both (according to the nature of the materials under treatment) auriferous rock sand or gravel, or any matter whatsoever containing 20 particles of metallic or native gold can be treated to such advantage that not only can the whole of the gold be extracted—a result not to be obtained by any process or contrivance, hitherto in use, as amalgamation, 25 sieve washing (commonly called "jigging") washing on inclined tables, in pans, "rockers" &c.; but the labor also can be performed in so short a time, with so much facility as regards mechanical power, bulk, convenience, &c. and at so small an expense, that 30 for the latter reasons alone it must become invaluable to the gold miner in general and the gold digger in particular.

In order to designate my invention with 35 brief distinctness and precision and to enable others to perceive, at a glance as it were, the substantial and, consequently, the real difference and distinction existing between an apparatus constructed after my 40 new and improved method; and any machine, apparatus or contrivance that may have heretofore been used in separating metallic or native gold from sand, gravel rocks &c.

45 I propose to call any and every vessel or apparatus, constructed on my new plan, a "sectional gold separator"; because the several and peculiar compartments or sections, of which it must needs be composed, and the 50 mode or modes of using them, respectively, for the efficient accomplishment of the specific purposes, hereafter set forth, constitute the essential novelty and practical value of my invention.

55 In the construction of my "sectional gold separators," I do not intend to confine my-

self to any particular size or form (though, as regards the latter, I consider the cylindrical or tubular and the square and oblong forms most desirable); nor do I limit my- 60 self to any particular material.

The following is a full clear and exact description of the construction of my new "sectional gold separators" and of the method of using the same for the purpose of 65 extracting or separating metallic or native gold from the sands, gravels, rocks or other matter in which it may be contained, reference being had to the annexed drawings making a part of this specification, the figures in which represent round and square vessels of any convenient size made of wood, metal or any suitable material, in such manner, that both the cylindrical and the square vessels (or vessels of any other suitable form 70 and size) may be and are to be divisible into several parts by horizontal and parallel movable compartments or sections fitting well one over the other. In the cylindrical or curved vessels these movable sections are 75 united, at one side, by a pivotal rod (hinges or any other suitable contrivance will answer the same purpose) of metal, upon which they may be moved in a circular direction, at pleasure, in a circular and horizontal direction, I think the best, though they may be moved vertically or wholly lifted off, in which latter case the pivotal rod or hinges would be dispensed with, and the sections 80 secured in their places in any other convenient manner, and when in their places for working, they are to be secured by hooks and eyes or other convenient fastenings as shown in Figures No. 1 and 2.

In the square vessels, the various compartments or sections are represented by a set of parallel frames or drawers without bottoms, which are made to slide one directly on top of the other in a straight direction as shown in Figs. No. 3 and 4, or the 95 compartments or sections may be made to move in a horizontal or vertical circular direction on a rod or hinges, or may be wholly lifted off, in which latter case the rod and hinges would be dispensed with, and the sections secured in their places in any convenient manner. When the sections however are not made to operate as scrapers it will be necessary to scrape off with some convenient tool.

To the lowermost section of either vessel is attached a single or double frame, mov-

able or not, containing a perforated plate corresponding in form and dimensions with the vessel, made of metal wood or any suitable material, as sieve cloth, sacking, &c. of 5 strength sufficient to support such quantity of auriferous sand, gravel, rock or other matter as would fill the vessel to the mark M—M, the compartments or sections being supposed to be in their places, and the vessel 10 air- and water-tight.

Before working, the vessel must be attached to some suitable contrivance, and in such a manner as to cause air or water, or both, at short and repeated intervals, vertically 15 to project such auriferous sand, gravel, rock and other material, (in fragments or particles suitably prepared and assorted) which may be placed in the vessel for treatment.

Fig. No. 5 shows a very convenient mode 20 of adapting, one or several such vessels, to a force pump which may be used for air with the valves V, V, or for water without the valves, and which can be made, by means of a lever or any other mechanical 25 contrivance to produce the effect desired by repeated up-and-downward motion of the piston, projecting the auriferous matter with sufficient force, and at such a rate, that it may have time, after each depression of 30 the piston and each consequent vertical projection of the auriferous matter to subside, while arranging itself according to the respective densities of its particles, the heaviest—viz, gold, going down to the lowest 35 compartment. After a sufficient number of strokes of the piston—say from twenty to a hundred strokes and more (according to the size of the particles composing the auriferous matter under treatment) it will 40 be found that the uppermost compartment which I call the “scraping section” will contain the lighter matter, without any admixture of gold; which lighter matter can be easily displaced by shifting the uppermost 45 compartment (viz, the “scraping section”) in question off from the next undermost as shown in Fig. No. 5, A. The lighter matter being thus removed, the “scraping section” is again brought back to 50 its original position for working; the removed stuff is replaced by fresh auriferous matter, and same process gone through with, and repeated until the lever compartment or compartments are filled with 55 gold, which is easily perceived and can even be regulated, to the greatest exactness, and without the slightest risk of losing any gold, in the following manner.

Previously to putting the auriferous mat-

ter into the “sectional gold separator”, I 60 fill the undermost compartment which I call the “gold section” with fine shot, (iron, brass, copper and other metallic filings or granules will answer the same purpose) 65 which I call the “protecting and regulating metallic grain”. The object of placing there this fine shot or “protecting and regulating metallic grain” is to protect the open interstices of the perforated bottom which I have named the “sieve plane,” from being 70 choked up with the fine clayey silicious or other light pulverulent matter which must needs form a great portion of the auriferous sands, gravels, crushed rock, &c, and which would tend to render the process of the 75 gold-separation unequal and tedious; as also to serve, by its final appearance, upon the shifting forward or sidewise (according to the square or round form of the “sectional gold separator”) of the “scraping 80 section”, at the upper level of the middle compartment,—called the “regulating section”, as a warning to the manipulator that, in the course and in consequence of repeating the afore described process of re-filling 85 and re-emptying the “scraping section”, the particles of gold, by virtue of their specific density, have at last filled out the “gold section”; lifting up, as they went down, the “regulating metallic grain” causing it to 90 fill out the “regulating section” (the dimensions of the latter and the former being the same) whence it has to be removed, for further use, by shifting in the manner described, said “regulating section” off from 95 the “gold section” allowing said “gold section” to be emptied, next, in a similar manner.

What I claim as my invention and desire to secure by Letters Patent is—

The construction of receptacles or vessels for containing auriferous and other ores, earths etc., to be treated or separated by water or air as above described, is making the said receptacle or vessels of two, three or 100 more sections arranged one above another perpendicularly so that they may be slid off in succession in a horizontal direction, or otherwise removed, to remove the refuse matter separated from the metal in the first 105 or top section, and the several or other layers of stratified matter contained in the other sections according to their respective specific gravities.

E. LEWIS SEYMOUR.
